CONVERTIBLE SWING AND ROCKING CRIB

George H. Hodgson, Tampa, Fla., assignor to
E. L. Dawson, Rattlesnake, Fla.

Application March 2, 1950, Serial No. 147,237

5 Claims. (Cl. 155—44)

1

The present invention relates to improvements in convertible swing and rocking crib and has for an object to provide a piece of furniture which will serve both as a swing and a crib, and in which swinging side sections are provided to cooperate with fixed end sections and a bottom or bed to either form a complete crib enclosure, or when the side sections are both swung to one side of the furniture to provide a back for the swing and to leave the seat of the swing open at one side for occupancy.

Another object of the invention is to provide a convertible swing and crib in which rockers are detachably mounted in connection with the end structures of the furniture to enable such furniture to be supported upon the ground.

A further object of the invention is to provide a convertible swing and rocking crib in which the construction is strong with reinforced end portions arranged to demountably receive the rockers.

With the foregoing and other objects in view, the invention will be more fully described herein-after and more particularly pointed out in the appended claims.

In the drawings in which like parts are denoted by like reference characters throughout the several views:

Figure 1 is a perspective view of the improved convertible swing and rocking crib as constructed in accordance with the present invention and illustrated as arranged for use as a swing.

Figure 2 is an exploded perspective view showing one of the swinging side sections.

Figure 3 is a vertical, sectional view taken on an enlarged scale on the line 3—3 in Figure 1.

Figure 4 is a bottom plain view of the furniture.

Figure 5 is a perspective view of the device arranged for use as a rocking crib.

Figure 6 is a perspective view, with parts broken away and parts shown in section of a form of rocker construction employed.

Figure 7 is a transverse section taken on the line 7—7 in Figure 5.

Figure 8 is a fragmentary longitudinal section taken on the line 8—8 in Figure 7.

Referring more particularly to the drawings, 10 designates a pair of spaced longitudinal rails which are connected together by end and intermediate cross sills 11 which may be glued, nailed, or otherwise secured to the longitudinal rails 10.

As seen to best advantage in Figure 4, the ends of the cross-sills 11 are seated in mortises 13 made in the inner faces of the longitudinal rails 10.

2

Slats 12 are secured to the sills 11 and preferably run substantially parallel to the longitudinal rails 10.

As appears in Figures 3 and 7, the cross sills 11 are offset below the upper edges of the longitudinal rails 10 by approximately the thickness of the slats 12, which brings the top surfaces of the slats 12 flush with the top edges of the rails 10. The ends of the longitudinal rails 10 project beyond the end cross sills 11.

The foregoing construction constitutes a bed or bottom for the swing-crib.

Upon this bottom construction are erected fixed end frames comprising side posts 14 to which are fastened the vertically-disposed slats 15, and corner posts 16.

The vertical slats 15 are nailed or otherwise secured to the inner faces of the side posts 14 so that the side posts 14 lie wholly outside the vertical plane in which the slats 15 are disposed. The arrangement makes for smooth and uninterrupted ends for the crib or sides of the swing. The bottom vertical slats 15 may engage the upper surfaces of the bottom horizontal slats 12.

25 The lower ends of the side posts 14 project below the horizontal slats 12 and enter the spaces between the projecting ends of the longitudinal rails 10 to which they may be affixed. The lower projecting ends of the side posts 14 may also be affixed to the end cross sills 11.

The corner posts 16 are fitted against the outer side faces of the side posts 14 and may be affixed thereto. The lower ends of the corner posts 16 rest upon the upper edges of the extended ends of the longitudinal rails 10. These duplex posts 14, 16 constitute sturdy reinforcements at the corner portions of the furniture. Each pair of posts 14, 16 are preferably flush as to their outer end faces, but the inner portions of the corner posts 16 will preferably extend inwardly of the inner faces of the side posts 14 by the thickness of the vertical slats 15 so that such slats 15 and the corner posts 16 are flush as to their inner faces.

40 The end frames are preferably capped by flat strips 17 which constitute arm rests for the swing and head and foot pieces for the crib.

Guide bars 18 and 19 are affixed to outer portions of the end frames. The upper guide bars 18 extend in common against the outer flush faces of the posts 14, 16 and are secured to such posts at both ends of the guide bars. Such upper guide bars 18 are also fitted along their upper edges against lower edges of the flat strips 17 which overhang the outer sides of the posts 14, 16 for this purpose.

The lower guide bars 19 extend across the space between the outer extended ends of the longitudinal rails 10 and preferably these lower guide bars 19 have their ends abutted against inner faces of the projecting ends of the longitudinal rails 10, said rails projecting beyond the outer faces of the posts 14, 16 for this purpose. The lower guide bars 19 may be affixed to the side posts 14 and also to the longitudinal rails 10 if desired.

The two guide bars 18, 19, at each end of the furniture, are in substantially vertical alignment and are spaced by the posts from the vertical tiers of slats 15 so that between these guide bars 18, 19 and the vertical slats 15 are provided slideways which are enclosed at their ends by the posts 14, but which are open at their bottom portions to receive the rocker construction shown more particularly in Figure 6.

There are two side frames, one of which comprises the vertical slats 21 nailed or otherwise secured to uprights 22 affixed to the upper and lower longitudinal strips 23 and 24.

The other side frame is similarly composed of vertical slats 25 secured to uprights 26 affixed to upper and lower longitudinal strips 27 and 28.

The ends of the side frames have secured thereto triangular or other brackets 29 and 30 having projecting end portions 31 and 32 which extend off the apex portions of the brackets 29, 30 in relatively opposite directions. In other words, from the viewpoint of Figure 1, the end projections 31 point upwardly while the end projections 32 are displaced downwardly so that the adjacent portions of the brackets 29, 30 are spaced vertically apart to avoid possible pinching of the hands or body when the operator swings one side frame on top of the other side frame to constitute a back for the swing. Pivot pins 33 pass through the registering end projections 31, 32, by which the side frames are both pivoted to the end frames.

As shown more particularly in Figure 3, the vertical shanks 34 of the hanger rods 35 pass down through the composite posts 14, 16 and are secured by nuts or other fastenings 36 beneath the posts. The upper portions of the hanger rods 35 converge upwardly and are looped at 37 to receive the chains or other supports for the swing.

The rocker construction is shown more particularly in Figure 6 and comprises the curved rocker bars 39 which support the spaced standards 40 which are connected together at their upper portions by the cross rods 41. The rocker standards 40 are so spaced by the rocker bars 39 and cross bars 41 and are so dimensioned that they will pass up through the slideways at the ends of the furniture with the standards 40, sliding in contact with the inner side faces of the side posts 14. The upper ends of the standards 40 may abut against the flat strips 17 and are confined by the guide bars 18, 19. Bolts and nuts or other fastenings 42 may be employed to secure the standards 40 to the end sills 11.

In the use of the device, by swinging both side frames to one side of the furniture as in Figure 1, the device is arranged for use as a swing and in this condition one side frame rests upon the other side frame and the two side frames form continuations of one another in the back of the furniture.

By swinging the upper side frame of Figure 1 to the opposite side of the furniture, a completely enclosed crib is provided which may be swung

from the swing chains 38 or may be caused to rest upon the rockers 39 after such rockers have been put into place, in which event a rocking crib is provided.

Although I have disclosed herein the best form of the invention known to me at this time, I reserve the right to all such modifications and changes as may come within the scope of the following claims.

10 What I claim is:

1. In an article of furniture, a bottom construction including longitudinally extending spaced side rails, upstanding end frames fixed on the ends of the bottom construction and including flat arm rests, ground engaging members having upstanding standards, means slidably mounting said standards in the end frames, releasable locking means retaining said standards in position in the end frames, a pair of side frames, each frame having parallel longitudinal rails connected by end bars, triangular brackets fixed at their major ends to the end bars and having offset minor ends, the brackets extending inwardly of the end frames and the bracket on the end of one frame overlapping at its minor end the bracket on the adjoining end of the other frame, pivot pins disposed through the overlapping minor ends of the brackets and secured in the arm rests, said side frames seating at one of their rails on the side rails of the bottom construction and extending upwardly and outwardly therefrom.

2. In an article of furniture, a bottom construction including a pair of spaced parallel longitudinal rails, cross sills transversely extending between the rails slightly inwardly from the opposing ends thereof and secured to said rails, upstanding side posts secured to the cross sills, corner posts mounted on the rails and abutting the side posts with the outer faces of the side posts flush with the adjoining side faces of the corner posts, slats secured to the inner faces of the side posts and extending transversely therebetween in vertically spaced fashion, vertically spaced guide bars extending transversely between the side posts and secured to the outer faces thereof, said guide bars forming slideways with the slats and the cross sills, arm rests secured to the upper guide bar and the upper slat and forming a stop wall for the slideways, standards slidably received in the slideways, ground engaging means carried by the lower ends of the said standards and releasable locking means for securing the standards in place in the slideways.

3. In an article of furniture, an end frame construction comprising spaced parallel rails, a cross sill connected to said rails and extending transversely therebetween slightly inwardly from the outer ends thereof, end posts fixed to the cross sill, vertically spaced slats transversely connected between the end posts and secured to the inner faces thereof, a pair of vertically spaced guide bars paralleling the slats and secured to the outer faces of the end posts, the uppermost guide bar and uppermost slat having their upper edges flush, an arm rest mounted on the upper edges of said slat and guide bar, standards slidably disposed between the slats and the guide bars, the inward sliding movement of the standards being limited by the engagement thereof with the arm rest and means for locking the standards in position.

4. In an article of furniture, an end frame construction comprising spaced parallel rails, a cross sill connected to said rails and extending transversely therebetween slightly inwardly from the

outer ends thereof, end posts fixed to the cross sill, vertically spaced slats transversely connected between the end posts and secured to the inner faces thereof, a pair of vertically spaced guide bars paralleling the slats and secured to the outer faces of the end posts, the uppermost guide bar and uppermost slat having their upper edges flush, an arm rest mounted on the upper edges of said slat and guide bar, standards slidably disposed between the slats and the guide bars, the inward sliding movement of the standards being limited by the engagement thereof with the arm rest and means for locking the standards in position, said last means including bolts connecting the standards to the cross sill.

5. In an article of furniture, an end frame construction comprising spaced parallel rails, a cross sill connected to said rails and extending transversely therebetween slightly inwardly from the outer ends thereof, end posts fixed to the cross sill, vertically spaced slats transversely connected between the end posts and secured to the inner faces thereof, vertically spaced guide bars paralleling the slats and secured to the outer faces of the end posts, the uppermost guide bar and uppermost slat having their upper edges flush, an arm rest secured on the upper edges of said

slat and guide bar, standards slidably disposed between the slats and the guide bars, the inward sliding movement of the standards being limited by the engagement thereof with the arm rest, means for locking the standards in position, side frames pivotally carried by the arm rest and having triangular laterally extending end brackets, the brackets having offset overlapping minor ends and a pivot pin disposed through the overlapping minor ends of the brackets and secured in the inner side of the arm rest.

GEORGE H. HODGSON.
